UNITED STATES PATENT OFFICE.

PHINEAS H. ADAMS, JR., AND ORSEMAS T. X. ADAMS, OF CHICAGO, ILLINOIS,
ASSIGNORS TO MELINDA PECK, OF SAME PLACE.

APPARATUS FOR USE IN DECOMPOSING METALLIC SALTS AND DESULPHURIZING ORES.

SPECIFICATION forming part of Letters Patent No. 399,117, dated March 5, 1889.

Application filed January 3, 1889. Serial No. 295,363. (No model.)

To all whom it may concern:

Be it known that we, PHINEAS H. ADAMS, Jr., and ORSEMAS T. X. ADAMS, citizens of the United States, residing at Chicago, Illinois, 5 have invented certain new and useful Improvements in Apparatus for Use in Decomposing Metallic Salts and Desulphurizing Ores, of which the following is a specification.

The object of our invention is to improve 10 an apparatus for mechanically decomposing chemical compounds, metallic salts, and desulphurizing ores or their resulting material, when the substances treated are in a molten condition, by the action of centrifugal force; 15 and our invention consists in the features hereinafter described and claimed.

In the drawings, Figure 1 is a vertical section of the apparatus, showing the lower portion of the running-gear in elevation. Fig. 20 2 is a plan view of a section taken in the line 2 2 of Fig. 1; and Fig. 3 is a vertical section of the annular tub, hereinafter described, with a slight modification in the cover.

In making our improved apparatus for decomposing chemical compounds, metallic salts or salts of metal, and desulphurizing ores, we make a receiving-vessel, V, constructed and adapted to receive the substances to be treated when in a molten condition.

30 This receiving-vessel is mounted and rests upon an actuating-shaft, to which it is fixed or keyed in such a way that by the rotation of the shaft the receiving-vessel will be revolved. The receiving-vessel may be made 35 in such a way as will secure the required strength and reduce the conduction of heat from the interior to the exterior. It may be surrounded by curbing and have a removable bottom to facilitate the removal of 40 the material which is not thrown off at the top by the action of centrifugal force, and in other respects it may be made as will be calculated to subserve the end in view and permit of its being rotated at a high rate of speed

45 for the separation of particles of different degrees of density in the matter treated. Many of its parts and the details of their construction, as they do not form the special subject-matter of our present claims, need not be 50 more fully described, as they will be sufficiently understood from an inspection of the drawings.

Surrounding this receiving-vessel V we provide what may be termed "an annular tub," B, adapted to fit around, preferably, the upper part of the mouth or neck of the receiving-vessel and extending down some distance below the top, as shown in Fig. 1. This annular tub may be supported in brackets C or by other suitable supports. It may be of such depth and capacity as to receive and retain a 60 considerable quantity of molten material as it is thrown off by the action of centrifugal force, and it may be supplied with a discharge spout or orifice, through which the molten material can flow off as it reaches the same into 65 a car or other means for conveying it away. Means may also be provided for removing the annular tub whenever desired, and to this end we prefer to provide it with ears D, in which a hook or bail operated by a crane or 70 other convenient means may be inserted whenever it is desired to remove the tub, in which case the top or cover of the apparatus must of course first be removed. We prefer to interpose between the inner wall of the 75 tub and the outer wall of the receiving-vessel an annular casing or wall, E, which will serve in a measure to prevent the radiation of heat through from one vessel to the other.

We provide the annular tub with a cover, 80 F, with its central portion immediately over the mouth of the receiving-vessel preferably depressed, as shown in Figs. 1 and 3. This central depressed portion, G, may consist either of a separate piece fitting into an opening, as shown in Fig. 1, or may be formed integral with the cover, as shown in Fig. 3. Of course in either case it will be provided with a central hole or opening, through which the molten material may be admitted to the receiving-vessel to be treated. The depressed portion of the cover, whether made as a separate piece or as an integral part, is intended to be brought down close enough to the mouth of the receiving-vessel to serve as a cover for 95 such vessel, leaving only sufficient space to permit the material which is thrown off by the action of the centrifugal force in fine particles or streams to be discharged between it and the top of the receiving-vessel. The employment of this cover serves to retain the heat both in the receiving-vessel and in the 100

annular tub, so that the material in the annular tub is constantly kept in a heated or fluid condition, so that it can flow off at the spout, to be conveyed away, as above described.

What we regard as new, and desire to secure by Letters Patent, is—

1. In an apparatus for decomposing metallic salts or salts of metals and desulphurizing ores when in a molten state, the combination of a revolute receiving-vessel adapted to receive molten material to be treated, an annular tub surrounding the same and adapted to receive the molten material discharged from the mouth of the receiving-vessel, a removable cover for such tub to retain the heat of the molten material therein, a revolute actuating-shaft rotating the receiving-vessel as it revolves, and means for rotating the actuating-shaft, substantially as described.

2. In an apparatus for decomposing metallic salts or salts of metals and desulphurizing ores when in a molten state, the combination

of a revolute receiving-vessel adapted to receive molten material to be treated, an annular tub surrounding the same and adapted to receive the molten material discharged from the mouth of the receiving-vessel, a removable cover for such tub to retain the heat of the molten material therein having a depressed central portion forming a cover over the neck or mouth of the receiving-vessel, with space between the cover and the neck or mouth to permit the discharging material to escape therefrom, whereby the heat in the receiving-vessel is largely retained, a revolute actuating-shaft rotating the receiving-vessel as it revolves, and means for rotating the actuating-shaft, substantially as described.

PHINEAS H. ADAMS, JR.
ORSEMAS T. X. ADAMS.
